UNITED STATES PATENT OFFICE.

CLIFFORD G. RUST, OF MARION, INDIANA.

MUSIC-LEAF TURNER.

1,144,917.

Specification of Letters Patent. Patented June 29, 1915.

Application filed April 1, 1914. Serial No. 828,835.

To all whom it may concern:

Be it known that I, CLIFFORD G. RUST, a citizen of the United States, residing at Marion, in the county of Grant and State of Indiana, have invented new and useful Improvements in Music-Leaf Turners, of which the following is a specification.

The invention relates to music leaf turning devices, and more particularly to the class of music leaf turners adapted to be mounted upon pianos or other like instruments, or upon music stands or racks to be used by orchestras, bands, etc.

The primary object of the invention is the provision of a music leaf turner wherein it will enable the automatic turning of music sheets of any size either forwardly or backwardly, thus making it possible for repeating the music, and also which can be actuated with the feet of the operator of the instrument so that the player will have free use of the hands at all times for playing this instrument.

Another object of the invention is the provision of a device of this character wherein the leaves of music will be successively turned singly without necessitating the handling of each leaf by the operator of the instrument, thus obviating interruption in the playing of the same and avoiding inconvenience to the player.

A further object of the invention is the provision of a device of this character which is controlled solely by the feet of the operator, and will automatically turn the leaves of music on depressing the foot pedals, one pedal being designed to operate the device for turning the leaves in one direction, while the other pedal is designed to operate the device for reversing the turning action of the leaves.

A still further object of the invention is the provision of a device of this character wherein the mechanism thereof is of novel form, possessing few parts, and is readily and easily operated.

A still further object of the invention is the provision of a device of this character which is extremely simple in construction, reliable and efficient in its operation, and inexpensive in manufacture.

With these and other objects in view, the invention consists in the construction, combination and arrangement of parts as will be hereinafter fully described, illustrated in

the accompanying drawings, and pointed out in the claim hereunto appended.

In the drawings:—Figure 1 is a perspective view of a support for leaf music, showing the music leaf turner constructed in accordance with the invention applied. Fig. 2 is a rear elevation thereof. Fig. 3 is a vertical transverse sectional view through the same. Fig. 4 is a sectional view on the line 4—4 of Fig. 2. Fig. 5 is a perspective view of the ratchet mechanism.

Similar reference characters indicate corresponding parts throughout the several views of the drawings.

Referring to the drawings in detail, A designates a portion of a music support, which may be the front wall of a piano or other musical instrument, or the stand of a music rack or the like, and B the music leaf turning mechanism hereinafter fully described in detail.

It is to be understood that the music leaf turning mechanism can be readily attached to the casing of the piano or to a music stand or rack without requiring any alteration in the construction thereof.

The music leaf turning mechanism comprises a two-part cylindrical housing or casing 10, one part thereof being fitted or telescoped within the other, and these parts have integrally formed therewith perforated ears 11 through which are passed suitable fasteners 12 connecting the casing to the music support A at the inner or outer face thereof and at a point centrally with respect to the instrument rack or stand. Rotatably fitted or held within the casing 10 is a series of cup-shaped interfitting sleeves 13, 14, 15 and 16, respectively, it being understood of course that any number of sleeves may be employed, while superimposed upon the latter sleeve 16 is a ring 17, and in these sleeves and the ring are engaged music leaf turning arms 18 which extend through a cut-away portion forming an opening 19 transversely in the tapered end 20 of the casing 10, the said end being extended above the upper edge of the support A to permit the arms 18 to swing arcuately beyond the plane of the support which constitutes a rest for the music. Each arm 18 has detachably connected thereto a suitable clip which is also detachably connected to the leaf or sheet of music so that the same will move with the arm when shifted, in a manner presently de-

scribed. The opening 19 in the casing is formed by cutting away in a transverse direction a portion of the said casing at the tapered end 20 thereof and at one side only 5 of the same, so as to not interfere with the swinging of the arms 18 from one side of the device to the other.

Passed centrally through the sleeves and ring is a slideable rod 21 formed with a 10 groove 22 therein for a portion of its length, the same being formed with a curvature 23, and into this groove 22 engage the pins 24 in the respective sleeves and ring held within the casing 10, so that on the sliding of the 15 rod 21 through the casing the sleeves and ring will be partially rotated for the swinging of the arms 18 to effect the turning of the leaves of the music. Carried by the casing 10 is a hook 25 which forms a hanger 20 to be detachably engaged by the ring 26 on the music. This is only done when the music is made up of a plurality of leaves, but when the music includes a single leaf the same is detachably clipped to one of the arms 18 of 25 the turner. It is of course to be understood that any number of turning arms 18 can be employed and also that the music can be detachably connected therewith and to the support in any suitable manner.

30 In event that there are a number of leaves to the book of music it is necessary to fasten a hook member 27 to each leaf, which member is adapted for detachable connection to an arm 18 for the hanging of the leaf therefrom; as will be apparent in Fig. 1 of the drawing.

Connected to the casing 10 is a sleeve 28 formed with a circular portion 29 in which is rotatably supported a cog gear 30, the 40 same meshing with cog teeth 31 formed on the rod 21, while integral with the said gear 30 and spaced therefrom is a ratchet disk 32, and arranged at opposite sides of this disk and loosely connected to the axle or 45 stud 33 supporting the gear 30 are ratchet arms or levers 34 and 35 respectively, each carrying a spring held pivot dog 36 which is adapted to engage the teeth on the ratchet gear 32 for the locking of the lever with the 50 said gear 30 to rotate the same. The casing 10 is formed with a boss 28^a which is adapted to frictionally engage in a correspondingly shaped socket formed in one end of the sleeve 28 so that the latter and the said casing 55 can be detachably joined to each other. The levers normally abut an extension 37 formed on the casing 10, and are adapted for swinging movement in reverse directions to each other so that the gear 30 can be rotated 60 in reverse directions on operating the respective levers 34 and 35, which have connected thereto springs 38 adapted to normally hold the levers 34 and 35 in contact with the abutment extension 37 and to move 65 the same to normal position after being

swung for shifting the rod 21 for the turning of the arms 18 in a direction to turn the sheets of the music.

Arranged below the support A contiguous to the floor or foundation upon which 70 rests the musical instrument or the stand or rack for the music, and suitably hinged to a stationary part of the instrument, rack or stand, is a pair of foot pedals 39 to which are connected flexible cables 40, the same 75 being also connected to the levers 34 and 35, respectively, the pedals 39 being lifted under the action of springs 41 which are suitably fastened to the musical instrument, rack or support, and on depressing the pedals 80 against the resistance of the springs 41 the automatic working of the music leaf turning mechanism is effected.

Mounted on opposite sides of the opening 85 in the support A are suitable brackets having outwardly projecting pairs of spaced resilient fingers 42, between which engage the music leaf turning arms 18 when shifted from right to left or vice versa, the fingers being designed to frictionally hold the said 90 arms 18 after the same have been turned, and in a manner as shown in Fig. 1 of the drawings.

In the operation of the device, assuming 95 that the leaves of a music sheet have been attached to the turning arms 18 by the hook members 27, and the said arms are positioned at the right hand side of the casing 10 of the device, now on depressing one of the foot treadles 39, that is to say, the one 100 toward the right, the arm or lever 35 is pulled upon so that the pawl 36 pivoted thereto will engage in one of the notches in the ratchet gear 32, so that on the lowering 105 of the lever 35, which is loose upon the shaft 33, the ratchet wheel 30 will rotate simultaneously with the ratchet gear 32, as both of the said gears are fixed to the said shaft 33, thus the gear 30 being in mesh with the 110 rack 31 on the rod 21 will cause the latter to slide, and in its movement the music turning arm 18 connected with the first page of the book will be turned, together with the 115 said page, this arm being turned by the engagement of the pin 24 in the curvature 23 of the slot 22 in the said rod. The pins 24 are mounted in the respective sleeves and rings held within the casing 10. On each movement of the rod 21 by operating the 120 lever 35, the respective arms 18 will be successively turned from the right hand side to the left hand side of the support. Should it be desired to turn back the sheets of music in successive order the other treadle 39 on the left hand side of the device is operated, 125 which moves the lever 34, and the pawl 36 thereon will engage the ratchet gear 32, causing it to rotate in a reverse direction from that heretofore set forth, and in a step by step manner; so that the arms will be 130

successively turned in a reverse direction for turning back the leaves in single order, as will be clearly apparent.

From the foregoing it is thought that the construction and manner of operation of the device will be clearly understood, and therefore a more extended explanation has been omitted.

What is claimed is:—

- 10 A music leaf turner comprising a support, a tubular housing fixed to the support and having a cut-away portion near the upper end at its front to form an opening, a plurality of cup-shaped sleeves within the said housing and fitted the one within the other, music leaf turning arms secured to the respective sleeve and projected through the opening in the housing, pins mounted in the sleeves, a rod slidable through the sleeves and having a slot provided with a curvature 20 therein receiving the said pins, teeth formed on the rod to form a rack, a gear meshing with the said rack, a ratchet gear fixed for rotation with the said first-named gear, 25 reversely swinging levers having pawls engageable with the ratchet gear, means for operating the levers independently of each other for turning the ratchet gear in reverse directions, and a coil spring having its ends fixed to the levers to hold the same in normal 30 position.

In testimony whereof I affix my signature in presence of two witnesses.

CLIFFORD G. RUST.
